WALL THERMOSTAT

Frederick M. Hill, Columbus, Ohio, assignor to
Ranco Incorporated, Columbus, Ohio

Filed Apr. 13, 1970, Ser. No. 22,397

Term of patent 14 years

Int. Cl. D10—07

U.S. Cl. D52—7

FIG. 1

FIG. 2

FIG. 3

FIG. 4

FIG. 5

FIG. 6

FIG. 1 is a top plan view of a wall thermostat showing my new design;

FIG. 2 is a front elevation thereof;

FIG. 3 is a bottom plan view thereof;

FIG. 4 is a side elevation thereof as seen from the left of FIG. 2;

FIG. 5 is a side elevation as seen from the right of FIG. 2; and

FIG. 6 is a sectional view of the thermostat taken substantially along line 6—6 of FIG. 2.

I claim:

The ornamental design for a wall thermostat, substantially as shown.
